TOILET OR UTILITY CASE OF LEATHER OR
LIKE MATERIAL

Leopold G. Stanley, Maplewood, N. J.

Application January 19, 1937, Serial No. 121,269

1 Claim. (Cl. 132—79)

This invention is a novel toilet or utility case of leather or like material. It is of the general class adapted for travel use, or for similar toilet or personal use, to contain light equipment or property, with a box member and a cover member and means of securely closing it, but leaving it quickly accessible. Being composed of leather or similar pliable or limp material it is distinguished from the different class of article consisting of a rigid box with hinged cover, such article being less convenient for packing or stowing away and not practically adapted to being closed securely by a continuous or zipper type of fastening means.

15 There is already well known a toilet or utility box composed entirely of leather and wholly limp or flexible, and with a hinged cover and a continuous or zipper fastening means. In practical use however such all-flexible case is subject to disadvantages. The article as a whole is liable to be too pliable and soft, so that when packed in baggage it is subject to crushing and possibly injury of contents. The hinge moreover between the box member and the cover is not steady and effective because it is formed at the top of a wall which is pliable, so that the hinge is not mechanically effective and durable. Further, the well known difficulty in starting the zipper closing operation is enhanced by the unsteady character 25 of the back wall at which the operation commences.

The objects of the present invention are to afford all of the advantages of the generally flexible type of case while avoiding the above mentioned objections. A further object is to afford a utility or toilet case which is compact, neat and attractive, also convenient in use and inexpensive of manufacture. A particular object is to afford a vertical rigidity at the critical point or back wall, thus giving the article as a whole a substantial degree of strength against crushing, as when the case is packed with other goods. A further object is to afford an article of the class referred to having a construction wherein the wall upon which the hinge is located is rigid and thus affords a steady fulcrum for the hinge. Another object is to afford a construction wherein the continuous type of fastener may be readily and conveniently operated for securely closing 40 and sealing the case. Other advantages will appear in the hereinafter following description of an illustrative embodiment of the invention.

To the attainment of the objects and advantages referred to the present invention consists in a toilet or utility case which is something be-

tween a rigid box and a completely flexible one and which avoids the disadvantages and attains the advantages of both. More particularly the invention consists in the novel combination and construction hereinafter described or disclosed 5 in the drawing.

In the accompanying drawing Fig. 1 is a perspective view of a toilet case or analogous case composed of leather or similar pliable material, showing the same in open position and with appropriate contents.

Fig. 2 is a front elevation and partial longitudinal section taken on the line 2—2 of Fig. 3, the case being shown closed and empty.

Fig. 3 is a vertical transverse section looking 15 from the right taken on the line 3—3 of Fig. 2.

Fig. 4 is a perspective of a rigid reinforcing plate or angle piece.

The case or utility box comprises in general a box member 5 and a cover member 6, composed 20 of leather or similar flexible or limp material as is desirable in this class of article. In Fig. 1 the box is shown as containing various articles 7 such as brushes, tubes, razor and the like, compactly arranged, and at the inner side of the cover are 25 shown suitable articles 8, as comb, file, etc., held in place by a strap 9. Other light or personal articles or property may be similarly accommodated or stowed in box or cover.

The box member 5 is composed of a bottom 30 wall 10 which is flat so that the case may rest flatwise upon a table or other support. The box member has also upright walls around the periphery of the box, namely, in the case of a square box, around the two ends and two sides. Thus 35 there is shown a back wall 11, a front wall 12, a right end wall 13 and a left end wall 14. The box may be other than quadrilateral, e. g. pentagonal, with one side as a back wall.

In the drawing the sectional showing of various plies or layers of material is exaggerated to facilitate disclosure. The exact arrangement of plies is not essential, so long as there are interior plies or linings covered both outside and inside the box by presentable material, needing 40 no detail description.

The cover member 6 is shown hinged to the box member 5 at the hinge line 15 located at the top edge of the hinge or back wall 11, so that the cover can freely swing up and down as shown 50 in the several figures. It is important in this class of article to secure the case at its periphery, i. e., around its ends and front side when closed, and for this purpose there is shown a continuous fastening, typically represented by the well 55

known zipper fastening. Thus one of the two complementary portions 16 of the zipper fastening is shown applied around the top edges of the peripheral walls 12, 13 and 14. The other zipper member 17 is arranged correspondingly around the under side of the cover member, where a slight flange or tape 18 is preferably provided for the application of the zipper fastener. A locking means or runner 19 is shown in Figs. 1 and 2 10 by which the continuous fastener may be fastened or unfastened in a well known manner.

As already described the peripheral walls, except the hinge wall, namely, the end walls 13 and 14 and the front side wall 12 of the box member, 15 are limp or flexible so that the article as a whole partakes of the flexible character. In distinction however to having all four walls flexible or limp, with the present invention, the back side wall is rendered rigid and vertically stiff by a 20 suitable rigid means or metal plate or angle piece embodied therein. This feature is illustratively shown as afforded by an angle iron 20 composed of stiff plate material or metal, as sheet iron, with a horizontal leg or part 21 and an upright 25 leg or part 22, the former being embedded or concealed in the bottom 10 of the box and the latter being embedded or concealed within the upright back wall 11. An extra covering piece or leather pad 23 may be embodied in the back 30 wall coextensive with or larger than the upright part 22 of the rigid angle piece.

By the described arrangement and structure a contrast is afforded between the back or hinge wall and the other peripheral upright walls of 35 the box. The case as a whole is generally flexible as is desirable, whereas the wall 11 upon which the cover member is hinged is rigid and therefore steady and upright. The article thus produced may be considered as semi-flexible, and it has 40 advantages absent from a case that is completely flexible and absent from a case that is completely rigid. The stiff and upright back wall protects the case against crushing, giving sufficient stability to the case as a whole for practical protection, as when packing the case within a suitcase or other baggage, without losing its desirable 45 generally limp and easily handled character. The case as a whole preserves its character and shape, whereas an all-pliable case tends gradual-

ly to flatten and wrinkle in an unsightly manner. The rigid vertical back wall affords a steady fulcrum for the hinge of the cover, rendering the hinge action both more efficient and durable. Moreover the rigid back wall affords a solid and firm basis for the operation of the zipper, especially in the starting of the runner for the opening and closing of the case, an operation not free from manual difficulty. 5

In practical use the toilet case of this invention 10 is found to possess a desirable and salable character not existing in otherwise similar cases. The article may be described as semi-flexible, being in this respect an improvement over either a completely stiff case or a completely limp one. 15 In the matter of manufacture the invention hereof has the advantage that it is inexpensive to construct. Leather or leather substitutes and ordinary limp or soft filling may be used for three of the upright walls, at minimum expense; 20 while for the stiffening of the back wall only a single inexpensive angle iron is necessary, embedded in the bottom and back wall.

I claim:

A utility box of leather or similar limp material consisting of the box body of substantial depth adapted to rest flatwise on a support and a connected flat shallow box cover, with fastening means on the box body and cover members to secure them together when closed; said box 25 body having a flat bottom and upstanding peripheral walls of substantially the full depth of the box extending entirely and continuously around the front and the ends and the back side of the box, such front and end walls being relatively flexible by reason of the limp material of which they are composed, but there being a stiff plate embodied in said upstanding back wall with a right-angled extension into said flat bottom thereby to render the back wall rigid vertically as compared with the other walls; and the box cover being hinged at its back edge to the top edge of such rigidly upstanding back wall of the box body; whereby the utility box 30 as a whole is flexible whereas the rigid rear wall of the box body presents a steady hinge mounting for the box cover. 35
